UNITED STATES PATENT OFFICE.

ARTHUR W. LYDA, OF NORTH CANTON, OHIO.

LIFE-RAFT.

1,369,289. Specification of Letters Patent. Patented Feb. 22, 1921.

Application filed May 29, 1918. Serial No. 237,339.

To all whom it may concern:

Be it known that I, ARTHUR W. LYDA, a citizen of the United States, residing at North Canton, in the county of Stark and State of Ohio, have invented a new and useful Life-Raft, of which the following is a specification.

My invention relates to combined torpedo net and life raft for vessels.

The objects of the present invention are, first, to provide a life raft or supplemental deck so constructed that it will lie parallel with the sides of the vessel, second, to provide a netting or torpedo guard and adjustment for the netting and torpedo guard so that it can be placed in position to protect the vessel and also to elevate the torpedo guard so as not to decrease the speed of the vessel when out of the danger zone, third, to provide means for elevating and lowering the torpedo guard from the bridge of the vessel, and fourth, to so connect the life raft that it can be instantly opened or detached if desired, and thereby release the vessel.

With these objects in view the invention consists in the novel construction and arrangement of parts hereinafter described, illustrated in the accompanying drawings, and particularly pointed out in the appended claim, it being understood that various changes in the form, proportions, size and minor details of construction may be made within the scope of the appended claim, without departing from the spirit or sacrificing any of the advantages of the invention.

In the accompanying drawings:

Figure 1 is a perspective view of a vessel provided with a combination life raft and torpedo net.

Fig. 2 is a top view showing a portion of the life raft.

Fig. 3 is a transverse section of the life raft showing the netting in lowered position.

Fig. 4 is a similar view showing the netting elevated.

Fig. 5 is an enlarged view of the torpedo net.

Similar numerals of reference indicate corresponding parts throughout the several figures of the drawings.

In the accompanying drawings, 1 represents the vessel in a conventional way and 55 within itself has no specific reference to the present invention, except to applying my

improvements thereto. The life raft or supplemental decks 2 are formed of a length to correspond with the length of the vessel and are constructed of sufficient size to 60 carry passengers, crew, freight, supplies and such other articles as may be necessary in order to save lives. The life raft is composed of, or made up of two members, said members are located upon opposite sides of 65 the vessel and are hinged together at their ends by means of suitable pins such as 3, best illustrated in Fig. 2. The life raft is propelled by the contact of the bow of the vessel against the ends of the life raft. In 70 case of the backing of the vessel it will be propelled by the stern coming in contact with the inner ends of the life raft members so that the life raft will move with the vessel and be in position to be occupied by passengers and crew of the vessel and also such articles as may be necessary to place upon the life raft. It will be understood that the ends of the life raft 2 should be provided with suitable flanges 4 having eyes 5 75 through which the pins 3 are passed in substantially the same manner as the connection of the leaves of an ordinary hinge.

To the vertical sides 6 of the life raft are connected the brackets 7, to which brackets 85 are pivoted the swinging arms 8. About mid-way between the outer ends of the arms 8 and their pivotal points are connected the cables 9, which cables are wound around suitable drums 10 mounted upon the shafts 90 11, which shafts are rotated by suitable connections from the bridge or other place of the vessel and are actuated preferably by electric motor. To the outer ends of the arms 8 are connected the net carrying arms 95 12, to which are attached the torpedo guards or nets 13.

In the perspective view the torpedo nets are shown in a conventional way, but I prefer to form the torpedo nets of hollow rings 100 13^a connected together as shown in Fig. 5. These hollow rings are connected together by loops or their equivalents 14^a, and should be water tight, thereby adding buoyancy to the torpedo guard proper. By forming the rings hollow they are comparatively light and yet will be formed of sufficient strength to turn the course of a torpedo by the movement of the guard and the vessel carrying the guard.

When the vessel is moved through the water outside of the danger zones the net is

brought into the position shown in Fig. 4, and when the boat reaches the danger zone the torpedo net or guard is lowered as shown in Fig. 3, by which arrangement the 5 guard will protect the sides of the vessel, owing to the fact that if a torpedo strikes the guard it will be shunted by the movement of the vessel, but if in the event an explosion should take place it will be less liable to injure the vessel; and for this purpose the 10 guard is spaced some distance from the sides of the vessel.

For the purpose of preventing the net carrying arms from swinging into a position other than vertical when lowered, the loops 15 15 are provided, which loops surround the arms 12 and their ends are pivoted to the arms 8, by which arrangement the arms 12 are held in substantially true vertical position. If in the event the vessel should be 20 sunk cables can be thrown from one life raft member to another, by which arrangement a temporary raft can be provided, there being sufficient cables to support any 25 pontoon structure that may be desired. In order to have the cables in position for use the life raft should be provided with a number of drums or spools 15 around which the cables may be wound, but can be readily 30 unwound and thrown across from one life raft member to the other and secured. These cable spools may be located in seats provided upon the life raft, thereby saving room.

35 To hold the upper ends of the guard carrying arms 12 in position and prevent any outward movement when the guards are lowered as shown in Fig. 3 chains or their equivalents 16 are provided, which chains

are connected at their outer ends to the upper ends of the arms 12 and the inner ends of said chains are connected to the life raft in any convenient and well known manner. 40

It will be understood that in order to protect the bow and stern of the vessel the torpedo guard should be located at front and rear and by this arrangement the entire 45 vessel will be protected.

If in the event the vessel should become disabled the life raft members can be easily 50 detached at either end and the vessel moved out after which the life raft members can be brought together and connected, thereby constituting a life boat well adapted to carry passengers and crew together with freight. 55 It will be understood that my invention can be applied to freight-going vessels and if desired suitable guns may be mounted upon the life raft for protection after the vessel has been destroyed as it will be understood 60 that ammunition can be readily transported from the vessel to the life raft or ammunition may be carried upon the life raft.

Having fully described my invention what I claim as new and desire to secure by Letters Patent, is—

In a device of the character described, the combination of a vessel, a life raft carried by said vessel, and surrounding the same, said life raft formed in sections and the sections hinged together and means for releasing the sections at one of their ends. 70

In testimony that I claim the above, I have hereunto subscribed my name.

ARTHUR W. LYDA.
